UNITED STATES PATENT OFFICE

149,661

DESIGN FOR A WRIST WATCH BRACELET

Henry Miller, Newark, N. J.

Application March 25, 1947, Serial No. 137,865

Term of patent 3½ years

(Cl. D45—4)

To all whom it may concern:

Be it known that I, Henry Miller, a citizen of the United States, residing at Newark, in the county of Essex and State of New Jersey, have invented a new, original, and ornamental Design for Wrist Watch Bracelet, of which the following is a specification, reference being had to the accompanying drawings, forming a part thereof.

In the drawings:

Fig. 1 is a top plan view of a wrist watch band showing my new design, and

Fig. 2 is an edge elevational view thereof.

I claim:

The ornamental design for a wrist watch bracelet, as shown.

HENRY MILLER.
